DESIGN FOR A CONTAINER CAP

John Hoch, Corona, Long Island, N. Y.

Application September 12, 1938, Serial No. 79,850

Term of patent 14 years

To all whom it may concern:

Be it known that I, John Hoch, a citizen of Germany and resident of Corona, Long Island, in the Borough of Queens, county of Queens, city and State of New York, have invented a new, original, and ornamental Design for a Container Cap, of which the following is a specification, reference being had to the accompanying drawing, forming part thereof.

Fig. 1 is a top plan view of a container cap showing my new design.

Fig. 2 is a front elevation of the same.

Fig. 3 is a vertical section of the same showing particularly the beveled lower flange on the cap.

I claim:

The ornamental design for a container cap, as shown.

JOHN HOCH.
